(57) **CLAIM**

The ornamental design for a drainage connecting pipe, as shown.

DESCRIPTION

FIG. 1 is a front view of a drainage connecting pipe according to the present application;

FIG. 2 is a rear view of the drainage connecting pipe;

FIG. 3 is a left view of the drainage connecting pipe;

FIG. 4 is a right view of the drainage connecting pipe;

FIG. 5 is a top view of the drainage connecting pipe;

FIG. 6 is a bottom view of the drainage connecting pipe; and,

FIG. 7 is a perspective view of the drainage connecting pipe.
